UNITED STATES PATENT OFFICE.

JAMES C. GORMAN, JR., OF MANSFIELD, OHIO, ASSIGNOR TO THE BARNES MANUFACTURING COMPANY, OF MANSFIELD, OHIO, A CORPORATION OF OHIO.

DIAPHRAGM-PUMP.

1,296,503.

Specification of Letters Patent.

Patented Mar. 4, 1919.

Application filed May 7, 1917. Serial No. 167,005.

To all whom it may concern:

Be it known that I, JAMES C. GORMAN, Jr., a citizen of the United States, residing at Mansfield, in the county of Richland and 5 State of Ohio, have invented certain new and useful Improvements in Diaphragm-Pumps; and I do hereby declare the following to be a full, clear, and exact description of the invention, such as will enable others 10 skilled in the art to which it appertains to make and use the same.

This invention relates to improvements in diaphragm pumps and one of the objects thereof is to provide a structure whereby the 15 valve of the pump is assured a lift to and from its seat in the same direction as the movement imparted to the diaphragm.

Another object of this invention is to provide a structure whereby the valve operating mechanism is protected from foreign matter in the shape of dirt or stones, whereby the correct seating of the valve is assured. 20

Another object of this invention is to provide a structure whereby the valve may be 25 removed and repaired or replaced without dismantling any of the coöperating structure of the pump.

Another object of the invention is to provide a structure consisting of the minimum 30 parts, which is cheaply made and which can be easily and quickly assembled.

The invention further comprises novel details of arrangement and combinations of parts that will be more fully hereinafter set 35 forth and pointed out in the following claims.

Referring to the drawings in which similar reference characters indicate corresponding parts, and in which—

40 Figure 1 is a section of the improved diaphragm pump;

Fig. 2 is a plan view of the valve seat casting member, the hollow posts thereof being shown in section; and

45 Fig. 3 is an elevation of the valve, the stem thereof shown as projecting into the sleeve.

The pump casing comprises lower and upper members 1 and 2 confining peripherally between them, by any suitable means, such as the bolts 3, the usual rubber diaphragm 4, provided with the central aperture 5. Secured to the top of the upper pump casing 2 in any approved manner is a

standard 6 provided with a pivotal mounting 7 for the operating lever 8 which in the present instance has an operating connection 9 at its free end adapted to impart to it the usual reciprocating movement. Substantially at its center, the lever 8 is provided with a second pivotal connection 10 having an internally threaded cap 11 adapted to have threaded thereinto the tubular valve-stem guide 12 which passes through a hole in a cross-bar or other rigid member 60 of the pump structure or casing and has its lower end firmly secured to a yoke 13 by means of the nuts 14 and 15; said yoke being secured upon diametrically opposite tubular projections 20, of a casting 16, carried by 70 the diaphragm, as hereinafter described.

The rubber diaphragm 4 is held between two disk castings 16 and 17 preferably of steel, the upper casting 16 being in the form of a disk, and provided with a central opening 18 which registers with the aperture of the diaphragm. The upper flat face of the disk casting 16 has an annular flange extending around the margin of the opening therein to form a seat 19 for the valve hereinafter described. This disk 16 on its upper face is also provided with two upstanding integral tubular projections or hollow posts 20 through which pass the bolts or other fastening members 21, the same also extending 85 through the rubber diaphragm, lower clamping disk 17, and the upper yoke 13 and provided on their upper extremities with threaded portions for the reception of nuts 22 whereby the whole is held in assembled 90 relation. Obviously any convenient means may be used for fastening these parts together.

Adapted to rest on the valve seat 19 is the valve, which may consist of a disk of sheet 95 rubber 23 held between two disk castings 24 and 25 preferably of steel through the center of which passes the steel valve stem 26 adapted to be attached thereto by means of the nut 27 and this stem projects up into 100 the tube 12 thereby allowing a reciprocating movement of the stem in said tube to seat and unseat the valve on the flanged seat 19.

In operation the usual reciprocatory movement given to the rocker lever 8 imparts a corresponding up and down movement to the diaphragm, on the up stroke of which the valve remains seated but upon

the reversal of which for its downward stroke the valve is raised by the water in the compartment beneath the diaphragm.

The construction above set forth assures a free and unrestricted vertical lift of the valve in a substantially straight line and prevents any dirt or stones from affecting the perfect seating of the valve since there are no operating parts or guiding means below the valve seat to obstruct the passage-way or on which any foreign matter carried by the water can lodge and there is nothing above or around the valve or the valve stem to obstruct the passage or on which foreign matter is liable to lodge and interfere with the movement and proper seating of the valve.

Moreover, this valve mechanism can be easily removed and without tearing the pump apart, it being only necessary to use a Stillson wrench to hold the stem of the valve and loosen the nut thereon with another wrench. The stem may then be pushed downward far enough to withdraw it from the hollow sleeve, whence the valve can be taken entirely out to replace the rubber face or to make other repairs.

Having thus described my invention, what I claim as new and desire to secure by Letters Patent is:

1. A diaphragm pump comprising a casing having an elastic diaphragm therein provided with a central opening, a ring-shaped casting on said diaphragm having a valve seated thereon over said opening, said casting being formed with tubular projections extending upwardly therefrom and having a cross-piece or yoke mounted thereon, and fastening bolts securing said diaphragm to said casting and extending

through said projections and through said yoke, a lever pivoted on said casing, and a tubular valve-stem guide depending from and pivoted at its upper end to said lever and having its lower end firmly secured to 45 said yoke; said valve having a stem slidably fitted in said guide, substantially as described.

2. A diaphragm pump comprising a casing having a diaphragm therein provided with a central opening, a lever pivoted on said casing and having pivoted thereto and depending therefrom a tubular valve-stem guide, said guide carrying at its lower end a yoke for attachment to said diaphragm, 50 a valve seated over said opening and having a stem slidably fitted in said guide, and means for connecting and securing said yoke to said diaphragm with said guide in vertical alinement and concentric with said opening and valve seat.

3. A diaphragm pump including in combination an operating lever, a tube depending from said lever and pivoted thereto at its upper end, an apertured diaphragm, a 55 valve controlling passage through the opening of said diaphragm, and provided with a valve-stem slideable in said tube, a yoke carried by said tube, and means for connecting said yoke to said diaphragm, including an apertured disk provided with a raised valve-seat and hollow, upstanding arms, both the valve-seat and the arms being integral with the disk.

In testimony whereof I affix my signature in the presence of two witnesses.

JAMES C. GORMAN, JR.
